SEWING MACHINE

Nathan Waldman and Emeric Polimac, Chicago,
Ill., assignors to George I. Goldwyn and Herman
Goldwyn, both of Chicago, Ill., copartners do-
ing business under name and style of Goldwyn
Brothers

Application May 16, 1939, Serial No. 273,960

4 Claims. (Cl. 112—162)

This invention relates to improvements in sewing machines and especially to commercial sewing machines, which are operated at relatively high speeds and are subject to hard usage and it consists of the matters hereinafter described and more particularly pointed out in the appended claims.

The invention is especially concerned with power sewing machines for forming an overcast or overedge stitch through cooperation between the needle and the looper and loop spreader in the manner well known. A machine of this kind is well adapted for sewing in connection with relatively heavy material such as burlap bagging and as an example thereof, attention is directed to the Goldwyn and Waldman Patent #2,013,884 of September 10, 1935.

One of the objects of the present invention is to provide a machine of this kind which may be run at higher speeds than has heretofore been possible and at the same time provide means for efficiently lubricating the rapidly moving parts and guard them against the entrance of dust and other foreign particles produced in sewing operations upon used burlap bags.

Another object of the invention is to provide a sewing machine of this kind wherein the parts are reduced to a minimum for simplicity and low cost production and which parts are so arranged that higher speeds are possible and practicable, partly through a novel gearing embodied in the operating mechanism of the machine and partly through the provision for an automatic lubrication of said parts.

The above mentioned objects of the invention, as well as others, together with the several advantages thereof will more fully appear as the specification proceeds.

In the drawings:

Fig. 1 is a longitudinal vertical sectional view through the operating parts of a sewing machine embodying the preferred form of the invention.

Fig. 2 is a transverse vertical sectional view through a part of the sewing machine as taken on the line 2—2 of Fig. 1.

Fig. 3 is a fragmentary top plan view on an enlarged scale of the bed or base plate of the sewing machine and associated parts therein.

Fig. 4 is a detail vertical sectional view through a part of the mechanism of the sewing machine as taken on the line 4—4 of Fig. 3.

Fig. 5 is a detail view in end elevation, on a scale reduced from that of Fig. 3, of the feed

mechanism of the sewing machine and will be more fully referred to later.

Referring now in detail to that embodiment of the invention illustrated in the accompanying drawings, 10 indicates as a whole the substantially elongated, rectangular bed or base plate of the machine adapted for attachment in any suitable manner upon a support such as a bench or table, not shown herein. This bed plate forms the bottom of an open top casing 11 of a somewhat irregular shape and of a substantial height, the greater part of said casing forming a mechanism compartment 12. The open top end of the casing is faced off to be engaged by the bottom end of the upright hollow standard portion 13 of 15 a substantially horizontally disposed hollow arm 14. This hollow arm terminates in a head 15, the open end of which is closed by a removable plate 16.

The casing 11 includes longitudinally extending upright front and rear walls 17 and 18, intermediate walls 19 and 20, and an upright right hand end wall 21. Said casing also includes left hand offset end wall portions 22—23 which connect the ends of the wall 19 with the walls 18 and 25 17 respectively and a short left hand end wall portion 24 that connects the wall 20 with the wall 17. This arrangement of the wall portions best appears in Fig. 3. The wall portions 19, 20 and 23 cooperate to define a recess 25 that is open at 30 its left hand end and in which recess, as will later appear, are located the looper and loop spreader of the mechanism of the sewing machine. Rising from the bed plate near the open end of the recess 25 is a boss 26 arranged coaxially with the needle 35 of the sewing machine and which will be referred to later.

A horizontally disposed shaft 27 is arranged longitudinally in the casing, in line with the wall part 19 and which shaft constitutes the main 40 drive shaft of the sewing machine. This shaft extends through and is journaled at one end in the wall 19 and extends through and is journaled at its other end in a boss 21a on the end wall 21 of the casing. Said shaft also extends 45 through and is journaled at a point between its ends, in an upright boss 28 on the bed plate 10. A pulley 29 (see Fig. 2) is connected to that end of the shaft 27 outside of the standard portion 13 whereby said shaft may be driven from a 50 suitable source of power.

A pinion 30 is fixed to the shaft 27 between the boss 28 and the wall 21 and the hub of this pinion, which faces toward said wall is made as an eccentric 31. A thrust bearing 32 is arranged 55

on the shaft 27 between said hub 31 and the boss 21a in which the associated end of the shaft 27 is journaled. A bevel gear 33 is fixed on the shaft 27 between the wall 19 and the boss 28 5 and the hub 34 of this gear is formed as an eccentric. A thrust bearing 35 is arranged on the shaft 27 between the gear hub 34 and the face of said wall 19.

Bevel gears 36 and 37 are disposed upon opposite sides of the boss 28 so as to mesh with the bevel gear 33, all of said gears being of the same size. To provide a rotative bearing for the gears 36-37, studs 38 are fixed in and extend from opposite sides of the boss 28. An anti-friction bearing 39 is carried by each stud, the gear being held against displacement by means of an internal shoulder 40 formed on the hub 41 of each gear and an internal locking ring 42 having a threaded engagement with the inner end of each gear. The hubs 41 of the gears 36 and 37, each carry a crank pin 43 and 44 respectively. This arrangement best appears in Fig. 3.

A vertically disposed pump casing or barrel 45 (see Fig. 1) is fixed to the base plate 10 in line with and below the eccentric hub 41. This pump barrel has an inlet orifice 46 in one side and a duct 47 leads from the outlet side of the pump casing to a point of discharge, as will later appear. A spring-pressed plunger 48 is disposed 25 in the top end of the pump barrel and its extremity rides in engagement with the eccentric hub 31. In the rotation of the shaft 27, the "high" side of the hub 31 will depress the plunger 48 to impart the discharge stroke thereto and 30 the spring of the plunger, before mentioned, will lift the latter as the "low" side of the hub approaches the same to provide the suction stroke for the pump.

50 indicates a rock shaft arranged parallel with 40 and adjacent the wall 18. This shaft is journaled at one end in a boss 51 on said wall and its other end is journaled in and extends through the wall 22 of the casing. Upstanding arms 53 are fixed to the shaft 50 substantially in line with the eccentric hub 34 of the bevel gear 33. One 45 end of a connecting rod 54 is connected to said arms and the other end of said rod is made as a strap 55 that surrounds said hub 34. When the shaft 27 is rotating, it is apparent that a rocking movement is imparted to the shaft 50 through the eccentric hub, the connecting rod and the arms just above mentioned.

That end of the shaft 50 which extends 55 through the wall 22 has upright arms 56 fixed thereto and which arms carry a pin 57. Operatively connected to the pin is the rear end of a feed bar 58, the front end of which is made to operatively engage upon an eccentric 59 on the extremity of the shaft 27. The front end of said 60 feed bar carries a feed plate 60 to project up through a suitable throat plate (not shown) carried on a part of a base flange on the standard 13. It is apparent that by reason of the pin 57 and the eccentric 59, the feed plate will engage 65 the material operated upon to feed the same in the conventional manner. The feed plate mechanism just described appears in Fig. 5.

61 and 62 indicate the rock shafts for the looper and loop spreader respectively. The loop spreader rock shaft 62 is journaled in bosses 63 and 64 respectively, made as integral parts of the walls 17 and 20 near the wall 24. This shaft which is disposed substantially horizontal, extends at an acute angle to the longitudinal me- 75 dian plane of the feed bar and in which plane is

also located the needle boss 26 before mentioned, on the bed plate.

The looper rock shaft 61, which is journaled near its ends in bearing bosses 65 and 66 respectively, is also arranged in substantially a horizontal plane and at an acute angle to the longitudinal plane of the feed bar 58. The acute angle of the looper rock shaft, however, is somewhat different from that of the loop spreader rock shaft 61.

For imparting rocking movement to said rock shafts 61-62, the following construction is provided. An arm 67 is fixed to the rock shaft 62 between the bosses 63-64 and this arm is operatively connected to one end of a pitman rod 15 68, the other end of which is operatively engaged with the crank pin 43 on the hub of bevel gear 37. An arm 69 is fixed to the rock shaft 61 near the boss 66 and said arm is operatively connected to one end of a pitman rod 70, the other end of 20 which is operatively connected to the crank pin 44 on the hub of the bevel gear 36. It is apparent that when the shaft 27 is being driven, a rocking movement is imparted to both rock shafts 61-62 through the parts above mentioned.

A looper 71 is operatively secured to the rear end of the shaft 61 and a loop spreader 72 is operatively secured to the front end of the shaft 62, the looper and the loop spreader being located substantially within the recess 25 before mentioned. If desired, a spreader loop retainer (not shown) may be employed on the shaft 62 in connection with the loop spreader. The looper and the loop spreader just above mentioned cooperate with an associated needle 74 in forming the stitch made and which is an overcast or overedge stitch.

In the formation of the stitch, the needle when descending, carries its thread through the fabric or bagging to a point below the throat plate (not shown). When the needle is ascending, slack 40 thread is formed which is forced out from the rear of the needle in the form of a loop which the looper 71 with its thread enters in passing from left to right. When the looper has reached the end of its stroke to the right, the rocking relation between the two rock shafts 61-62 is so timed that the spreader 72 rises and engages the thread at the front of the looper and carries it to the left of the needle. The needle on its next descent enters the loop of the thread thus formed 45 and which is then tightened in the fabric by the action of the looper as the next stitch is formed.

A horizontally disposed shaft 75 (see Fig. 1) extends longitudinally in the hollow arm beneath a chamber 76 in the top end thereof and the bottom of this chamber is formed by a horizontally disposed wall 77. The shaft 75 is journaled at its right hand end in a boss 78 formed as a part of the standard 13 and said shaft is journaled at its left hand end in a second boss 79 formed as a 60 part of the overhanging arm 14. Said second boss is arranged below and in line with a part of a vertical wall 80 that separates the chamber 76 from the interior of the head 15. In this respect, it is pointed out that the bottom 65 portion of the hollow arm 14, where it joins the bottom end of the head is formed as a splash well or recess 81.

A pinion 82 is secured to the shaft 75 near the boss 78 and this pinion meshes with an idler gear 70 83, which in turn meshes with the pinion 30 on the shaft 27. The gear 83 is journaled on a stub shaft 84 that is operatively secured at one end in a boss 85 in the standard 13.

The pinions 30 and 82 are the same in size. 75

Therefore the shaft 75 is driven from the shaft 27 in the same direction and at a 1 to 1 ratio. The conduit 47 before mentioned has its top end directed to discharge into the chamber 76. A part 5 of the bottom wall 77 of said chamber, in line with and above the pinion 82 is somewhat thickened and a hole 86 is formed therein. In the wall 80 there is provided a longitudinal passage-way 87 whereby communication is afforded between the chamber 76 and the interior of the head 15. To fill the chamber 76 with a lubricant, an opening is provided in the top wall of the hollow arm 14 near the wall 80 and a plug 88 is removably secured in said hole. In that 15 face of the wall 80 that opens into the head 15 there is provided a vertically disposed groove 90, the passage-way 87 opening at one end directly into said groove.

91 indicates the needle bar of the machine that 20 is disposed in the head 15 and is mounted in the top and bottom portions thereof for a vertically reciprocating guided movement. The bottom end of this bar carries the usual clamp (not shown) whereby the needle 74 previously mentioned is 25 operatively secured to said bar. A head block 92 is secured to a part of the needle bar within the head and this block includes a stub shaft 93 that carries a roller 94 which in turn has a vertical guided movement in the groove 90 before mentioned.

That end of the shaft 75 extending into the head 15 has a disc 95 secured thereon and said disc is of such diameter as to dip into the well or recess 81. The disc 95 carries a crank pin 35 96 and one end of a pitman rod 97 is journalled on said pin and the other end of said pitman rod is journalled on the stub shaft 93 between the head block 92 and the roller 94 respectively.

Of course, the usual presser foot bars, tension 40 devices and other parts that are conventional in overcast sewing machines are employed in the present machine, but as such bars, devices and parts are not essential to an understanding of the invention involved herein, they are not shown 45 or described in detail herein.

In the operation of the machine above described, let it be assumed that a quantity of oil 50 is present in the base. When the shaft 27 is being driven, it will function through the gears 38, 83 and 82 respectively to drive the shaft 75 at the ratio and in the direction before mentioned. As the shaft 75 is thus being driven, it is apparent that the crank 96 through the rod 97 will produce a reciprocating movement of the 55 needle bar 91 and its associated needle.

In the rotation of the shaft 27, it will through the bevel gear 33 drive the two companion bevel gears 36 and 37 in opposite directions and this in turn through the mechanism before mentioned will rock the shafts 61 and 62 so that the looper 71 and the loop spreader 72 will be caused to function in connection with the needle 74 to produce the overcast stitches as previously described. As the shaft 27 is rotating, it will 60 65 act through the eccentric hubs of the gears 30 and 33 in one instance to cause the desired action of the feed plate and in another instance to actuate the pump.

In the actuation of the pump, it will function 70 on its suction stroke to draw oil in through the slit 46 and on its discharge stroke, it will discharge oil into the chamber 76. A part of the oil in the chamber 76 will drip down through the hole 86 onto the pinion 82 and from there 75 down to the gear 83 and the pinion 30 so that

these pinions and the gear run in a stream of oil.

A part of the oil in the chamber 76 will flow through the passageway 87 into the groove and a part thereof will lubricate the roller 94 and 5 the remainder will drip down onto the disc for a lubrication of that end of the shaft 75 journalled in the boss and a part thereof will drain into the well 81. The oil in this well is thrown back upwardly by the disc 95 so that ample 10 lubrication of adjacent parts is assured.

When the well 81 is filled, the excess will overflow therefrom to run down into the base and a part of this oil will discharge or drip upon the thrust bearing 35 and associated parts in the base 15 whereby they are efficiently lubricated.

It is apparent that the greater number of parts are rotary ones and that they are thoroughly 20 lubricated. Thus, it is possible to run the machine at higher speeds and with less wear on said 25 parts so that the machine functions to produce a greater number of stitches in less time than heretofore possible in an overcast stitch sewing machine. With the gear drive before mentioned, noise and vibration are reduced to a 30 minimum so that the period of usefulness of the machine is materially increased and the necessity of frequent servicings is reduced. All operating parts for the needle bar, the looper and the looper spreader are enclosed and are thus 35 protected against the entrance of dust thereto and the oil is maintained in a cleaner condition.

While in describing the invention, we have referred in detail to the form, arrangement and 40 construction of the parts thereof, the same is to be considered only in the illustrative sense, so that we do not wish to be limited thereto except as may be specifically set forth in the appended 45 claims.

We claim as our invention:

1. In a sewing machine, the combination of a 50 casing, a shaft in said casing and journalled at its ends in upright portions thereof, an upright boss in said casing in which said shaft is journalled, a bevel gear fixed to said shaft adjacent 55 said boss, a rockable looper and loop spreader arranged outside of said casing for cooperating with the needle of the sewing machine in forming stitches, rock shafts for the looper and the 60 loop spreader respectively arranged in the casing, other bevel gears arranged on said boss and meshing with and driven by said first mentioned bevel gear, means carried by said boss and upon which said other bevel gears are journalled, and 65 means operatively connecting said rock shafts to said other bevel gears and translating the rotation of said other bevel gears into rocking movement of said rock shafts.

2. In a sewing machine, the combination of a 70 casing, a shaft in said casing and journalled at its ends in upright portions thereof, an upright boss in said casing in which said shaft is journalled, a bevel gear fixed to said shaft adjacent 75 said boss, a rockable looper and loop spreader arranged outside of said casing for cooperating with the needle of the sewing machine in forming stitches, rock shafts for the looper and the loop spreader respectively arranged in the casing, other bevel gears arranged on said boss and meshing with and driven by said first mentioned bevelled gear, studs arranged substantially in the plane of the axis of said shaft and fixed to and extending outwardly from opposite sides of said 80 boss and upon which said other bevel gears are 85

journalled, a crank arm on each of said other bevel gears, a rock arm on each rock shaft and a rod connecting each crank arm with a rock arm.

3. In a sewing machine, the combination of a casing, a shaft in said casing and journalled at its ends in upright portions thereof, an upright boss in said casing and in which a mid portion of said shaft is journalled, a bevel gear fixed to said shaft adjacent said boss, a rockable looper and loop spreader arranged outside of said casing for cooperating with the needle of the sewing machine in forming stitches, rock shafts for said looper and loop spreader respectively, arranged in the casing, studs arranged substantially in the plane of and extending at a right angle to the axis of said shaft, means for operatively securing the inner end of each stud to opposite sides of the boss, other bevel gears one associated with each stud and meshing with and driven by the first mentioned bevel gear, anti-friction bearing means between each stud and its associated beveled gear, means associated with each stud and the bevel gear thereon for holding the associated bearing in place and through said bearing holding the associated gear against endwise displacement from its stud, a crank arm on the outer end of each of said gears on said studs, a rock arm on each rock shaft and a rod connecting each crank arm with a rock arm.

4. In a sewing machine, the combination of a casing, a shaft in said casing and journalled at its ends in upright portions thereof, an upright boss in said casing in which said shaft is

journalled, a bevel gear fixed to said shaft adjacent and facing said boss, a rockable looper and loop spreader arranged outside of said casing for cooperating with the needle of the sewing machine in forming stitches, rock shafts for said looper and loop spreader respectively, arranged in the casing, studs arranged substantially in the plane of and extending at a right angle to the axis of said shaft, means for operatively securing the inner end of each stud to opposite sides of the boss, other bevel gears one associated with each stud and meshing with and driven by the first mentioned bevel gear, anti-friction bearing means between each stud and its associated beveled gear, means associated with each stud and the bevel gear thereon for holding the associated bearing in place and through said bearing holding the associated gear against endwise displacement from its stud, a crank arm on the outer end of each of said gears on said studs, a rock arm on each rock shaft and a rod connecting each crank arm with a rock arm.

NATHAN WALDMAN.
EMERIC POLIMAC.
